UNITED STATES PATENT OFFICE

OSWALD H. HANSEN, OF MILWAUKEE, WISCONSIN, ASSIGNOR TO HANSEN CANNING MACHINERY CORPORATION, OF CEDARBURG, WISCONSIN

CAN-FILLING MACHINE

Application filed November 12, 1925. Serial No. 68,511.

This invention relates in general to improvements in the art of measuring and packing fluent commodities, and relates more specifically to improvements in the construction and operation of machines for automatically and accurately filling containers such as tin cans with fluent substances such as a mixture of corn and milk.

An object of the invention is to provide an improved can filling machine which is simple in construction and efficient in operation.

Some of the more specific objects of the invention are as follows:—

To provide a compact filler having relatively few movable parts.

To provide a can filling machine having a relatively small can circle and operable at high speed without wasting material.

To provide a machine for filling receptacles with fluent substances, which will positively deliver an accurate quantity of material to each of the successive receptacles irrespective of the consistency of the substance.

To provide a filling machine in which dripping and splashing of the material is eliminated, and wherein overflowing of the cans when the filler is stopped, is positively prevented.

To provide can filling mechanism of variable capacity, the elements of which are readily adjustable to change the operating characteristics.

To provide a sanitary filler structure which may be conveniently assembled and dismantled for inspection and cleaning.

To provide an automatic filler in which the use of complicated valve mechanisms is avoided.

To provide a machine all parts of which may be manufactured at minimum cost and which may be operated and manipulated by a novice.

To provide various other improvements in the details of construction of can filling machines whereby the efficiency is enhanced to a maximum.

These and other objects of the invention will be apparent from the following description.

A clear conception of embodiments of the

various novel features and of the operation of devices constructed in accordance with the invention, may be had by referring to the drawings accompanying and forming a part of this specification in which like reference characters designate the same or similar parts in the various views.

Fig. 1 is a central vertical section through an improved can filling machine especially adapted to fill cans with fluent mixture such as corn and milk.

Fig. 2 is a part sectional front elevation of the improved can filling machine.

Fig. 3 is a horizontal section through the can filling machine taken directly above the can supply, discharge and transporting mechanisms.

Fig. 4 is a top view of the material supply and measuring mechanism of the improved can filling machine.

Fig. 5 is a development of the material measuring mechanism showing the measuring and discharge plungers in various positions of adjustment.

Fig. 6 is an enlarged fragmentary section through the material measuring mechanism, the section being taken through one of the measuring pockets and through the capacity varying mechanism.

Fig. 7 is a fragmentary development of a modified form of track mechanism for moving the discharge plungers.

The improved corn filler specifically illustrated in the drawings, comprises in general a stationary hopper 36 communicating with a conduit 50 and constituting a source of material supply; a stationary cup shaped casing 4 having a side inlet opening 22 and a bottom discharge opening 13 therein; a pocket element 3 rotatably supported within the casing 4 and forming an annular series of seven vertical substantially cylindrical measuring pockets 9; a displacement plunger 6 reciprocable within each of the pockets 9; a central rotary vertical drive shaft 2 for revolving the pockets 9 and the plungers 6 about the central axis of the casing 4; can supply mechanism for delivering empty cans 21 to the machine; a series of can hooks 28 operable by the shaft 2 and a guide 29 cooperating

therewith to transport the cans 21 through the machine beneath the pockets 9; can discharge mechanism for delivering the filled cans 21 from the machine; driving mechanism for the shaft 2 and for the can supply and discharge mechanisms; and stationary frames 10, 32 for supporting the material measuring and feeding and the can transferring mechanisms.

10 The hopper 36 may be disposed laterally of the casing 4 and above the measuring portions of the pockets 9 so that the fluent material is delivered by gravity through the conduit 50 to the successive pockets 9 and entrained air is free to escape upwardly through the conduit 50 and the hopper 36. The casing 4 besides providing a support for the shaft 2 and for the element 3, has a continuous annular outer wall the upper extremity of which 15 provides a stationary roller track 18 as shown in Figs. 1, 5 and 6. The pocket element 3 comprises an outer portion within which the pockets 9 are formed, a central sleeve member 45 rigidly attached to the outer portion 20 and having a lower recess engaging the elongated driving block 11 formed integral with the shaft 2, and a cut-off plate 5 rigidly attached to the lower end of the outer portion and sleeve member and having an annular series of downwardly converging discharge 25 orifices 12 disposed eccentrically of the pockets 9. The measuring pockets 9 have their sides remote from the axis and adjacent to the wall of the casing 4, open for communication 30 with the casing opening 22.

Each of the vertically reciprocable plungers 6 has a main body snugly fitting the adjacent cylindrical pocket 9, and also has a 40 detachable slide 7 snugly fitting the interior surface of the casing 4 and coacting with the side edges of the lateral openings in the pockets 9 to prevent rotation of the plungers within the pockets. The slides 7 are detachably connected to the plunger bodies by means 45 of pins 14, which rotatably support the plunger actuating rollers 8. The lower extremities of the plunger 6 and of the slides 7 are provided with central depressions 26 thus making the pressing faces of the plungers 50 concave with respect to the eccentric discharge orifices 12 so that the downwardly moving plungers will tend to urge all of the confined material directly toward and through these openings.

55 Cooperating with the stationary roller track 18 at the upper end of the wall of the casing 4, are vertically adjustable tracks 15, 16, 19, 20 and a removable normally fixed roller retainer 17, the latter of which is detachably secured to the casing 4 by means of bolts 58. The horizontal track section 20 and the inclined track sections 15, 19 are formed integral with each other and cooperate with portions of the track 18 to gradually 60 conduct the successive rollers 8 thereon and

therefrom irrespective of the position of adjustment of the movable tracks. The upper inclined track section 16 is rigidly attached to and is simultaneously adjustable with the lower sections 15, 19, 20 and cooperates with the roller retainer 17 to gradually conduct the rollers 8 from between the track sections 15, 16 irrespective of the position of adjustment of these sections. The rigidly interconnected simultaneously movable track sections 70 15, 16, 19, 20 are rigidly associated with two vertical movable sleeves 37 which coact with stationary sleeves 40 secured to the frame 10. Threaded blocks 38 secured within the upper portions of the movable sleeves 37 coact with the screw threaded upper ends of rods 39 which are rotatably supported within the stationary sleeves 40. A spiral gear 41 is secured to the lower end of each rod 39 and coacts with a spiral gear 42 associated with a cross-shaft 43. The cross-shaft 43 is journaled in the stationary frame 10 and is rotatable by means of a hand wheel 44 to rotate the rods 39 through the gears 41, 42. 75

As shown in Fig. 7, the vertically adjustable tracks 15, 16, 19, 20 of Fig. 5, may be replaced by other vertically adjustable tracks 23, 24, 25, 27 having steeper inclined portions, for the purpose of varying the plunger strokes. These substitute tracks are interchangeably cooperable with the threaded blocks 38 and with the fixed sleeves 40 and will fill cans 21 of larger size than those with which the tracks 15, 16, 19, 20 are intended to operate. The measuring and filling mechanism may be enclosed by means of a removable cover 46 as shown in Fig. 1, in order to prevent ingress of dirt. 90

The central vertical shaft 2 besides being journaled in the casing 4, has a lower bearing 105 in the cross frame 32. A bevel gear 30 is secured to the shaft 2 above its lower bearing, this gear 30 being drivingly connected to the can hooks 28 by means of vertical drive rods as shown in Fig. 1. A stationary can support 110 57 is supported by the frame 10 between the gear 30 and the can hooks 28. The gear 30 is rotatable by means of a bevel pinion 31 secured to one end of the horizontal power shaft 33 with the opposite end of which a driving pulley 34 is associated. The pulley 34 is drivingly connectible with the shaft 33 by virtue of a jaw clutch 59 which is operable with the aid of a lever 35 or by means of automatic stop mechanism 60 of the type disclosed in 115 Patent No. 1,557,455, granted October 13, 1925.

The can supply mechanism is of the type disclosed in Patent No. 1,339,060, granted May 4, 1920, and comprises a can supply chute 120 47 cooperating with a rotary can feed drum 48 having a helical feeding projection 49 thereon formed to deliver the successive empty cans upon the support 57 and into engagement with the successive can hooks 125 130

28. The feed drum 48 is rotatable by means of a horizontal shaft 52 journalled in the frame 10 and interchangeably operable by the gear 30 through the pinion 53, or by the hand wheel 51 associated with the outer end of the shaft 52.

The mechanism for delivering the filled cans 21 from the machine comprises in general a discharge disk 54 rotatable by means of a vertical shaft which is drivingly associated with the bevel gear 30, and a guide 55 adjustably supported above the disk 54 in a well known manner.

During normal operation of the filler, the supply hopper 36 is provided with a mixture of corn and milk or any other fluent substance, and the machine is set in motion by the application of power through the pulley 34, shaft 33, gear 30 and shafts 2, 52. As the pocket element 3 is rotated by means of the vertical shaft 2, the pockets 9 revolve about the axis of the shaft 2 and are successively placed in communication with the supply hopper 36 through the supply opening 22 and the conduit 50. When such communication is established, the plungers 6 are first elevated by the track 19 and are subsequently caused to travel horizontally in elevated position by the track 20 to completely fill a definite portion of each of the successive pockets 9 dependent upon the position of adjustment of the tracks 15, 16, 19, 20, see Fig. 5. As the successive pockets 9 are thus filled with measured batches of the material, they are cut off from the opening 22 and are subsequently brought in communication through their lower discharge orifices 12 with the delivery opening 13 of the casing 4. The plunger rollers 8 then enter the space between the inclined tracks 15, 16 and the plungers 6 are urged downwardly thereby forcing the measured batches of material from the pockets through the orifices 12 and the opening 13 into the cans 21 located below the pockets. The orifices 12 are retained open until the lower faces of the plungers reach their lowermost positions within the pockets 9 whereupon the orifices are again cut off and subsequent measuring is effected. The formation of the end 56 of the delivery opening 13 is such that as the orifices 12 are gradually advanced over the upwardly inclined upper surface of the end 56, the upwardly moving plungers 6 draw the liquid from this surface into the adjacent pockets and subsequent dripping of material is positively eliminated. The concave formation of the lower ends of the plungers 6 also insures complete delivery of the measured batches from the sides of the pockets 9 toward the discharge orifices 12. The successive filled cans 21 are delivered from the machine by the discharge disk 54 and guide 55, and the feed drum 48 automatically supplies empty cans 21 to the can hooks 28.

If it is desired to vary the fill, it is only nec-

essary to manipulate the adjusting hand wheel 44 to either raise or lower the movable tracks 15, 16, 19, 20 thereby automatically varying the effective volumes of all of the measuring pockets 9. Such adjustment may be effected without removing the enclosing cover 46. In case it is desired to operate on cans 21 having greater or less volume, the movable tracks 15, 16, 19, 20 may be replaced by tracks 23, 24, 25, 27 in an obvious manner. With the tracks adjusted to a predetermined position, every can 21 will receive a like quantity of material irrespective of the consistency of the mixture.

The formation of the end 56 of the discharge opening 13 effectively prevents waste of material by dripping and the downwardly converging delivery orifices 12 likewise effectively prevent waste of material by splashing. It will also be noted that the can circle is of larger diameter than the diameter of annularity of the orifices 12 and that this diameter of annularity is greater than that of the axes of the measuring pockets 9. This construction of the elements enables the pockets 9 to be placed very near to the central axis of rotation and consequently permits operation of the machine at relatively high speed without spilling the material. In view of the fact that each pocket 9 can only be supplied with a definite quantity of material exactly equal to the volume of the portion of the can 21 which is to be filled, the filler may be stopped at any time without danger of overfilling the cans as with the prior machines.

If it is desired to remove the plungers 6, it is only necessary to remove the cover 46 and to lift the successive plungers vertically from within the pockets 9 as they are brought to positions beyond the tracks 16, 17 by manipulation of the hand wheel 51. The tracks 15, 16, 19, 20 are simultaneously removable upon release of the set screws which normally hold the threaded blocks 38 within the sleeves 37 or by running these blocks off of the upper ends of the rods 39. The roller retainer is readily removable upon release of the bolts 58. The pocket element 3 is freely vertically removable from within the casing 4 upon removal of the plungers, whereupon the sleeve 45 and the cut-off plate 5 may be removed if desired.

It will be apparent that the operation of the filler is entirely automatic and that the various adjustments may be conveniently effected. The sleeve 45 and plate 5 facilitate manufacture of the rotor element 3, and the construction of the plungers 6 is likewise facilitated by making the slides 7 removable. The plate 5 entirely eliminates the use of complicated valve mechanism and the entire structure is extremely simple.

Some of the novel features of can filling machine construction disclosed but not

specifically claimed herein, form the subject of copending applications Serial No. 634,196, filed April 23, 1923, and Serial No. 9,466, filed February 16, 1925.

It should be understood that it is not desired to limit the invention to the exact details of construction and operation herein shown and described, for various modifications within the scope of the claims, may occur to persons skilled in the art.

10 It is claimed and desired to secure by Letters Patent:—

1. In combination, a source of fluent material supply, means forming a measuring pocket having a side inlet opening and a restricted lower end discharge opening, a casing embracing said pocket forming means, means for revolving said pocket within said casing about a vertical axis to intermittently move the same past said source, a plunger movable in said pocket to withdraw material from said source into said pocket through said side opening and to subsequently deliver said material from said pocket through said end opening, and means carried by said plunger and coacting with an end of said casing to move said plunger.

2. In combination, a source of fluent material supply, means forming a series of measuring pockets each having a lateral inlet opening for receiving material from said source and a restricted lower end discharge opening for delivering said material, a casing embracing said pocket forming means, means for moving said pockets in succession past said source to receive batches of material therefrom, and means associated with an end of said casing for delivering said batches from said pockets through said end openings.

3. In combination, a cylindrical cup shaped casing having an opening in the side wall and having another opening in the bottom thereof, an element forming an annular series of measuring pockets within said casing, said element having side openings for establishing communication between said pockets and said casing side opening and having a series of restricted end openings communicable with said casing bottom opening, and a plunger movable within each of said pockets.

4. In combination, means forming a series of movable measuring pockets each having an end discharge opening, and a plate coacting with the bottom of said means and having an opening communicable with said pocket discharge openings, the cut-off end of said plate opening being chamfered upwardly and in the direction of travel of said pockets to eliminate dripping.

5. In combination, an element forming a plurality of measuring pockets, said element comprising a hollow outer member, a central sleeve member, and an end plate member, means for simultaneously moving said mem-

bers about the central axis of said sleeve member, and a casing supporting said element and having supply and discharge openings communicable with said pockets.

6. In combination, a rotary element comprising an outer member forming a plurality of measuring pockets, an inner sleeve member attached to said outer member, and a perforated plate member attached to an end of said outer member, and a stationary casing rotatably supporting said element and having supply and discharge openings communicable with said pockets.

7. In combination, means forming a measuring pocket movable about an axis, a stationary casing cooperating with said means to inclose said pocket, a plunger movable within said pocket, a roller carried by said plunger and cooperable with a wall of said casing to move said plunger, and a roller retainer detachably associated with said casing adjacent to said wall, said plunger and roller being freely removable upon release of said retainer.

8. In combination, means forming a measuring pocket, a plunger movable within said pocket, a track for moving said plunger, a sleeve secured to said track, a stationary sleeve telescopically supporting said track sleeve, and a rod journaled in said stationary sleeve and having screw thread cooperation with said track.

9. In combination, means forming a measuring pocket, a plunger movable within said pocket, and means for adjusting the position of said plunger relative to said pocket, said adjusting means comprising inner and outer sleeves and a screw threaded rod for telescopically adjusting said sleeves.

10. In combination, means forming a pocket, a plunger movable within said pocket, a track for moving said plunger, an outer sleeve secured to said track, a threaded block secured to said sleeve, a stationary inner sleeve supporting said outer sleeve, and a threaded rod rotatable within said inner sleeve and coacting with said block to move said track.

11. In combination, a casing having a bore and an inlet opening communicating with the lower portion of said bore, means rotatable within said bore and forming a series of measuring pockets successively communicable with said opening, each of said pockets having a restricted lower end opening located closely adjacent to the surface of said bore and remote from the bore axis, and a plunger movable downwardly in each of said pockets.

12. In combination, a casing having a vertical bore and an inlet opening communicating with the lower portion of said bore, rotary means cooperating with the surface of said bore to form a series of measuring pockets successively communicable with said opening, each of said pockets having a lower end

opening of less than half the cross-sectional area of the corresponding pocket located closely adjacent to the surface of said bore, and a plunger movable downwardly in each of said pockets.

5 13. In combination, a casing having a vertical cylindrical bore and an inlet opening communicating with the lowermost portion of said bore, rotary means snugly fitting said bore and cooperating with the surface of said bore to form an annular series of measuring pockets successively communicable with said opening, each of said pockets having a relatively small restricted lower end opening located closely adjacent to the surface of said bore, and a plunger movable downwardly within each of said pockets.

10 14. In combination, a source of fluent material supply, means forming a series of measuring pockets each having an inlet formed to receive material laterally from said source and also having a restricted lower discharge opening, a casing embracing said pocket forming means, means for moving said pockets in succession past said source to receive batches of material therefrom, and means associated with said casing for delivering said batches from said pockets through said lower openings.

15 15. In combination, a source of fluent material supply, means forming an annular series of pockets each having an inlet formed to receive material laterally from said source and also having a restricted lower discharge opening, a casing having a cylindrical bore embracing said pocket forming means, means for revolving said pockets about the axis of said bore to move the same in succession past said source so as to admit material to said pockets through said inlets, and means associated with said casing for delivering said batches through said lower openings.

20 16. In combination, an element forming a plurality of measuring pockets, a plunger in each of said pockets, a casing embracing said element and having an end forming a restricted discharge opening for each of said pockets, the opposite end of said casing forming a track, and adjustable means cooperable with said track to move said plungers toward said openings.

25 17. In combination, an element forming a series of pockets each having a restricted discharge opening, a plunger in each of said pockets, a casing surrounding said element and having an end forming a track, and a movable track section cooperable with said casing track to move said plungers relative to said openings.

30 18. In testimony whereof, the signature of the inventor is affixed hereto.

OSWALD H. HANSEN.
